UNITED STATES PATENT OFFICE.

WILLIAM P. ALGER, OF WEST TROY, NEW YORK, ASSIGNOR OF ONE-HALF
TO CHARLES C. KELLEY, OF SAME PLACE.

DESIGN FOR A TOOL-HANDLE.

SPECIFICATION forming part of Design No. 22,221, dated February 14, 1893.

Application filed August 29, 1892. Serial No. 444,456. Term of patent 7 years.

To all whom it may concern:

Be it known that I, WILLIAM P. ALGER, a citizen of the United States, residing at West Troy, in the county of Albany and State of New York, have invented a new and original Design for Tool-Handles, of which the following is a specification.

The invention relates to a new and original design for handles of tools for dressing emery-wheels.

The object of the present invention is to provide a new and ornamental design for tool handles; and the essential feature resides in the shank of a tool having between the head and handle-portion a substantially octagonal portion provided with broadened or enlarged upper and lower faces.

In the drawings—Figure 1 is a perspective view of a tool handle showing my new design. Fig. 2 is a transverse sectional view of the shank.

Referring to the drawings, 1 designates a shank provided between the handle portion 2 and a head 3, with a substantially octagonal intermediate portion 4 having broadened or enlarged upper and lower faces 5 and 6, and beveled corner faces 7, and vertical side faces 8. The lower or handle portion 2 is corrugated.

What I claim is—

The design for a tool handle herein shown and described.

In testimony that I claim the foregoing as my own I have hereto affixed my signature in the presence of two witnesses.

WILLIAM P. ALGER.
